DISPLAY RACK

Jack L. Blum, Philadelphia, Pa.

Application October 13, 1948, Serial No. 54,224

5 Claims. (Cl. 211—89)

1

My invention relates to display racks, and it relates more particularly to racks for the display of a plurality of articles of merchandise, such as neckties or the like, for inspection and selection by intending purchasers.

The principal object of the present invention is to provide a rack or holder for displaying a number of articles, such as neckties or the like, for inspection and selection by intending purchasers, from which the selected articles may be readily removed without disturbing the orderly arrangement of the others.

A further object of the present invention is to provide a display rack or holder having improved means whereby an article may be inserted quickly and expeditiously to replace one which was previously removed.

A further object of the present invention is to provide a rack or holder, of the character described, having a plurality of clamping plates for holding articles to be displayed, with improved means for separating said clamping plates to permit the insertion of a portion of an article to replace one which had been previously removed.

More specifically considered, the present invention comprises certain improvements in the construction and arrangement of the necktie holder shown and described in my previous Letters Patent No. 2,253,841, dated August 26, 1941.

The nature and characteristic features of the present invention will be more readily understood from the following description, taken in connection with the accompanying drawings forming part hereof, in which:

Figure 1 is a side elevation of a necktie rackholder embodying the main features of the present invention, the bar on which the same is mounted being shown in section;

Fig. 2 is a top or plan view thereof;

Fig. 3 is a vertical section taken on the line 3—3 of Fig. 2;

Fig. 4 is a vertical section taken on the line 4—4 of Fig. 2;

Fig. 5 is a transverse vertical section taken on the line 5—5 of Fig. 2; and

Fig. 6 is a perspective view of one of the clamping plates detached, with one of the devices for spreading the clamping plates shown in place thereon.

It should, of course, be understood that the description and drawing herein are illustrative merely, and that various modifications and changes may be made in the structure disclosed without departing from the spirit of the invention.

2

Referring to the drawing as therein shown, 10 is a supporting bar or rod upon which the article holder of the present invention may be mounted. The rod or bar 10 may be supported in any desired manner, and at any preferred place, or the same may be a component part of a pedestal structure, not shown, for counter display.

It should, however, be understood that ordinarily a plurality of the holders of the present invention will usually be mounted on such a bar, however said bar may be supported. Of course, other means for supporting the holder may be used if desired.

The parts of the device of the present invention are mounted in a suitable frame having side plates 11 and 12, and an integral cross plate 13 at the front extending from one side plate 11 to the other side plate 12.

The frame may also include, at the rear, a cross plate 14 to which a parallel plate 15 is integrally attached by means of the top member 16 thereby to provide a channel for the purpose of mounting the frame on the supporting rod or bar 10.

The rear plate 15 of the frame is provided with an upward extension 17 bent over at the top as at 18 to provide a handle for manually gripping the device when it is to be removed from the supporting rod or bar 10. The side plates 11 and 12 of the frame may be secured to the rear plates 14 and 15 by means of tongues 19 extending through openings 44 and 45 in said plates 14 and 15 and having bent over portions 20 at the rear of the plate 15, and the supporting rod or bar 10 may be suitably notched as at 21 where the tongues extend across the channel provided by the portions 14, 15 and 16. The notches 21 serve to prevent the frame from sliding on the supporting rod or bar 10.

The frame is also provided with internally disposed guide bars 22 and 23 connected by a transverse bar 24 at the front. The bar 24 is secured to the transverse bar 13 of the main frame. The rear ends of the guide bars 22 and 23 extend through openings 46 in the rear plate 14 and are bent over as at 48 and 49 against the inner face of said plate 14 within the channel provided between the members 14 and 15. The guide bars 22 and 23 are slotted as at 25, for a purpose to be presently explained.

Slidably mounted on the bars 22 and 23 is a plurality of clamping plates 26, one of which is shown in detached perspective in Fig. 6 of the drawing, said plates 26 being suitably apertured as at 27 complementary to the guide bars 22 and

23. Each of the clamping plates 26 is bent over at its respective ends as at 28 and 29, thereby to provide means for mounting a separating device on each clamping plate 26.

The separating device is preferably made of round wire suitably bent and formed to provide a spindle 30, one end of which is journaled in the hole 47 provided in one of the bent over portions 28 and the other end of which is journaled in an angular cut-out 31 in the other bent-over portion 29. Intermediate the ends of the spindle portion of the separating device the same is bent at two places to provide arms 32 and 33, disposed between the bent-over end portions 28 and 29 of the clamping plate 26 and the guide bars 22 and 23.

The guide bars 22 and 23 are longitudinally slotted as at 25 for the passage therethrough of the spindle portion of the separating device.

Each of the clamping plates 26 is provided with a pair of holes 50 adapted to receive the ends of the arms 32 and 33 when the same are brought to their operative positions as hereinafter described and thus hold the plates 26 in separated positions.

One end of the spindle portion of the separating device extends through a slot 35 in the side plate 12 of the main frame, being bent as at 36 at right angles to the spindle portion and terminating in a circular coil 37 to provide a hand hold for selectively rotating the desired separating device to operate the same in a manner to be presently set forth.

A stop member 40, made of a suitable piece of wire, extends along the side of the side plate 12 of the main frame, the same being secured at its front end to the front end of said side plate 12 and extending through openings in the plates 14 and 15 at the rear end of the frame and being bent over as at 42 to hold the same in place.

A pair of coil springs 43 are mounted between the innermost of the clamping plates 26 and the rear plate 14 of the frame, said coil springs 43 serving to impel the clamping plates forwardly upon the guide bars 22 and 23. The coil springs 43 are secured against removal by having their respective end portions 51 and 52 bent inwardly and secured to the plates against which they abut. To insure the fastening of the springs 43 the end portions 51 thereof are passed through openings 53 provided by struck-out portions 54 of plate 14, and the end portions 52 of springs 43 are passed through openings 55 provided by struck-out portions 56 of the innermost of the clamping plates 26.

The operation of the device may now be readily understood. Whenever it is desired to separate an adjacent pair of clamping plates, the coil which provides the handle portion of the spreading device which is mounted on the rearmost of the two plates to be separated, is gripped by the operator, and turned forwardly to rotate the spindle about its axis in the journals provided in the bent-over ends 28 and 29 of the clamping plate. As the spindle member is thus rotated the arms 32 and 33 carried thereby will push against the clamping plate 26 immediately to the front thereof and cause the clamping plate upon which the spindle member is mounted to be moved to the rear against the tension of the coil springs 43.

When the spindle member is rotated to bring the arms 32 and 33 to the operative positions to separate a pair of clamping plates the handle portion 37 of the spreading member will be lim-

ited to approximately 90° of movement by means of the stop member 40 on the side of the side plate 12 of the main frame.

Also when the spindle member is rotated to bring the arms 32 and 33 to the operative positions to separate a pair of clamping plates, the ends of the arms 32 and 33 will be seated in the apertures 50 in the adjacent clamping plate so that the parts will be locked against return movement until the spindle is manually actuated by means of the arm provided at the end of the spindle device for that purpose.

It will, of course, be understood when a pair of clamping plates is thus separated, the clamping plates to the rear will also be pushed rearwardly when the separation takes place. When the pair of clamping plates 26 are thus spread, the folded neck band portion of a necktie may be inserted in the space thus provided and upon the return of the spreader to its normal inoperative position the coil springs will push the clamping plate forward thereby to grip the folded end of the necktie between the clamping plates.

After the folded end of the necktie has been inserted between the clamping plates the holder is then placed upon the supporting bar 10, as indicated in Figs. 1 and 2, and the tongue portion of the guide members which extend across the channel will serve to prevent the device from sliding lengthwise on the bar 10 by reason of said top plates engaging the notches provided in the bar 10 for that purpose.

It will be noted that the rod 40 provided along the side of the side member will serve as a limit to prevent the spreader from being rotated more than approximately 90° to the spreading position.

1. An article holder for a display rack comprising a frame having spaced guide bars, a plurality of parallel article clamping plates slidably mounted thereon, spring means impelling said plates to clamping positions, and each of said plates having means carried thereby to spread the same to increase the space between an adjacent pair of said plates to permit an article to be inserted in said space.

2. An article holder for a display rack comprising a frame having spaced guide bars, a plurality of parallel article clamping plates slidably mounted thereon, spring means simultaneously impelling all of said plates to clamping positions, and means for spreading said plates to increase the space between an adjacent pair of said plates whereby an article may be inserted in said space, said means comprising the provision on each of said clamping plates of a manually rotatable member journaled in portions of said plate and having means to engage and separate an adjacent plate, when rotated.

3. An article holder for a display rack comprising a frame having spaced guide bars, a plurality of article clamping plates mounted thereon, spring means simultaneously impelling all of said plates to clamping positions, and means for spreading said plates to increase the space between an adjacent pair of said plates whereby an article may be inserted in said space, said means comprising the provision on each of said clamping plates of a manually rotatable member journaled in portions of said plate, said member having arms adapted when said member is rotated to engage an adjacent plate and separate the same.

4. An article holder for a display rack comprising a frame having spaced guide bars, a plurality

of parallel article clamping plates mounted thereon, spring means simultaneously impelling all of said plates to clamping positions, and means for spreading said plates to increase the space between an adjacent pair of said plates whereby an article may be inserted in said space, said spreading means comprising the provision on each of said clamping plates of a member journaled in portions of said plate, said member having arms adapted when said member is rotated to engage an adjacent plate and separate the same, and said member having a hand lever on one end outside the frame for manually rotating said member.

5. An article holder for a display rack comprising a frame having spaced guide bars, a plurality of parallel article clamping plates mounted thereon, spring means simultaneously impelling all of said plates to clamping positions, and means for spreading said plates to increase the space between an adjacent pair of said plates whereby an article may be inserted in said space,

10 said spreading means comprising the provision on each of said clamping plates of a member journaled in portions of said plate, said member having arms adapted when said member is rotated to engage an adjacent plate and separate the same, said member having a hand lever on one end outside the frame for manually rotating said member, and recesses in said plates adapted to receive the ends of the aforesaid arms to hold the same in spreading positions.
